INTERNAL COMBUSTION ENGINE

Ralph M. Heintz, Cleveland, Ohio, assignor, by
mesne assignments, to Jack & Heintz, Inc.,
Cleveland, Ohio, a corporation of Ohio

Application May 8, 1943, Serial No. 486,265

5 Claims. (Cl. 123—56)

This invention relates to improvements in internal combustion engines of the four stroke cycle type.

The general object of the invention is to provide an improved four stroke cycle internal combustion engine utilizing crankcase compression for supercharging the cylinders. A further object is to provide a novel arrangement of valves, ports and fuel passages for a four stroke cycle engine so as to obtain the maximum supercharging effect from crankcase compression. An additional object is to provide a novel rotating sleeve valve arrangement for an internal combustion engine, enabling better cylinder head and combustion chamber design.

Additional objects and advantages will become apparent to those skilled in the art as the description proceeds in connection with the accompanying drawings in which:

Figure 1 is a sectional view taken longitudinally through the cylinders of an engine embodying the principles of the invention.

Figure 2 is a sectional view taken on the line 2—2 of Figure 1.

Figure 3 is a sectional view taken on the line 3—3 of Figure 1.

Figure 4 is a sectional view through another embodiment, showing the pistons in their extreme outward positions.

Figures 5 and 6 are sectional views taken on the lines 5—5 and 6—6 of Figure 4 respectively.

Figure 7 is a view taken on the line 7—7 of Figure 4 but showing the piston at the crankcase end of its stroke, and

Figure 8 is a fragmentary view taken as Figure 7, but with the parts in the same positions as in Figure 4.

The embodiment of the invention illustrated in Figures 1, 2 and 3 has two opposed cylinders 1 and 2 arranged on opposite sides of a central crankcase 3. Each cylinder contains a rotating sleeve valve 4 having exhaust ports 5 and intake ports 6 adapted to cooperate with exhaust ports 7 and inlet ports 8 in the cylinder. The lower end of each sleeve 4 may be provided with a ring gear 9 driven by short shafts 10 and 11 from the engine crankshaft 12. The crankshaft 12 is carried in bearings 13 and 14 and has two crank throws 15 and 16 for the connecting rods 17 on the pistons 18. The crank throw 15 includes a disc 19 having a segment 20 cut out to uncover the end of an inlet passage 21 connected with a pipe 22 leading to a carburetor 23 in the case of a carbureted engine. In a fuel injection engine the pipe 22 would of course lead

to the atmosphere instead of a carburetor. The end of the intake passage 21 is covered by the disc 19 except during that portion of the crankshaft revolution when the pistons are moving outwardly to admit a fresh charge, at which time the opening 20 will have uncovered the end of the intake passage.

The crankshaft throws 15 and 16 are arranged at a relative angle of 180 degrees so that the two pistons move outwardly and inwardly in unison, the timing being such that the two cylinders fire on alternate strokes. As the two pistons move outwardly the opening 20 uncovers the inlet passage 21 to draw in a fresh charge, the 15 crankcase being otherwise closed to the atmosphere. Assuming that one of the pistons 18 is about ready to move down on its cylinder suction stroke, the timing of the sleeve 4 will be such as to close the exhaust ports 5 and open intake ports 6. As the piston progresses in its cylinder suction stroke the exhaust ports remain closed and the inlet ports continue to open, so that when the top of the pistons clears the top of the inlet ports, they are wide open and the combustion space in the cylinder is placed in communication with the interior of the crankcase by way of passageway 24. It will be noted that by the time one piston has started to uncover the inlet ports 6 the other piston will have moved a similar distance inwardly so as to place the charge in the crankcase under considerable pressure before it is admitted to the cylinder whose intake ports are open. During the cylinder suction stroke of one piston as described, the other piston has been making a power stroke with its inlet valve closed so that at the time the piston which is on its cylinder suction stroke uncovers its inlet ports only the one cylinder receives a charge from the crankcase. After the said suction stroke the 40 piston then proceeds back on its cylinder compression stroke closing off the inlet ports and compressing the charge until the point of ignition, the exhaust ports remaining closed. During the power stroke the sleeve 4 maintains both the exhaust and inlet ports closed, the exhaust ports being subsequently opened for the exhaust stroke. At the completion of the exhaust stroke and at the beginning of the cylinder suction stroke the exhaust ports 5 are closed and the 45 cycle is repeated.

It will be seen that the compressive effect of the inward strokes of both pistons towards the crankcase are effective to compress the charge in the crankcase to supply a single cylinder, since 50 the two cylinders are supplied on alternate

strokes. In this manner a marked supercharging effect is obtained, the crankcase pressure being raised considerably above what would be obtained by the action of a single piston as in a two cycle engine.

Various numbers of exhaust ports may be employed, four being shown in the embodiment of Figures 1, 2 and 3, the width of the ports and the width of the wall portions between the ports being suitably proportioned to produce the desired type of engine indicator diagram. It will be seen then, that with four exhaust ports for a four cycle engine each sleeve should rotate 90 degrees from one exhaust to the next, or should make one revolution for eight revolutions of the crankshaft, the sleeves in the two cylinders being timed for alternate firing. That is to say that when one piston moves down on its cylinder suction stroke, the other piston is moving down on its power stroke and vice versa.

The inlet ports are also four in number and are arranged to be closed by the sleeve 4 during the lower part of the power stroke, and should be at least substantially fully open as long as they are uncovered by the pistons on the cylinder suction strokes.

Either fewer or more than four exhaust and inlet ports may obviously be used, the size and spacing of the ports being governed by the above considerations to produce the described functions. It is of course appreciated that increasing the number of ports reduces the speed at which the sleeves must rotate since if there was only one port the sleeve would be required to make a complete revolution for every two revolutions of the crankshaft.

The engine constructed according to the present invention is intended to be of relatively high speed wherein a strictly gas tight seal will not be required between the disc 19 and the inlet passage 21 to establish the desired crankcase pressure. If the invention is applied to low speed engines a resilient disc or other expedient may be embodied in the disc 19 to effect a better seal with the opening in the inlet passage 21 to prevent loss of pressure from the crankcase back to the atmosphere.

Figures 4 to 8 illustrate a further embodiment attaining a greater supercharging effect from crankcase compression. In this embodiment there are cylinders 101 and 102 connected with a crankcase 103, and rotary sleeve valves 104 in the cylinders. The cylinders are provided with exhaust ports 105, and a double set of inlet ports 106 and 107 connected by curved inlet passages 108. The sleeve valves 104 have exhaust ports 109 adapted to register with the cylinder exhaust ports 105 in one position of the sleeve, and a double set of inlet ports 110 and 111 adapted to register with the cylinder inlet ports 106 and 107 in another position of the sleeve, the lower end of the sleeve being provided with a ring gear 112 for rotation.

Bearings 120 and 121 in the crankcase carry a crankshaft 122 having crank throws 123 and 124 connected with pistons 125 and 126. Openings 127 in the piston skirts are aligned with the lower set of cylinder inlet ports 106 and are adapted to communicate with these ports when the pistons reach the ends of their cylinder suction strokes. Adjacent the bearing 121 is a crankcase inlet port 130 connected with an inlet passage 131 leading from a carburetor 132 in the case of a carbureted engine. In a fuel injection engine the passage 131 would lead directly to the

atmosphere. The port 130 is covered by a disc 133 on one side of the crank throw 124 when the pistons are moving inwardly toward the crankcase, the port being uncovered by a cut out segment 134 when the pistons are moving outwardly from the crankcase. Bearing blocks 135 and 136 are shaped to close off the ends of the crankcase close to the crank throws to keep the crankcase volume as small as possible so that the charge admitted to the crankcase by suction when the pistons are moving outwardly will be compressed to a pressure of several atmospheres when the pistons move inwardly. By operating the engine at a relatively high speed, and by allowing very little clearance between the disc 133 and the port 130, crankcase pressures having a satisfactory supercharging effect for high altitude operation are obtained. The present engine has particular utility for driving a large aircraft generator which may be secured on the flange bolts 137 for direct drive by the internally splined end 138 of the crankshaft.

The rotary sleeve valves 104 are preferably driven in opposite directions by a shaft 140 through idler gears 141, 142, and 143 as shown in Figures 5 and 6. It will be noted that for four stroke cycle operation the speed of rotation of the sleeves 104 will always be less than the speed of the crankshaft. In the embodiment shown in Figures 4 to 8 the sleeves 104 have six ports in each set, requiring a rotational speed of one-twelfth crankshaft speed. The width and spacing of the ports are determined by the amount of overtravel and other practical considerations involved in producing a desired type of engine cycle. In the case of the inlet ports 106 and 107 it is desirable to have them at least substantially fully open during the time the piston has any part of ports 106 uncovered. This requires that ports 106 and 107 be opened during the downward motion (with respect to the cylinder head) of the piston on the cylinder suction stroke, and that the closing of these ports be accomplished during the cylinder compression stroke after the piston has passed the ports in its upward travel.

The cylinders have cylinder heads 145 with sealing rings 146 bearing against the upper ends of sleeve valves 104. The cylinder heads 145 have central portions extending within the cylinders and sleeves to provide in each cylinder a circular combustion chamber having an unrestricted lower surface contour established by the shape of the piston head and having a substantially unrestricted upper surface contour established by the shape of the lower or inner surface of the cylinder head whereby the determination and selection of the shape and volume of the combustion chamber is capable of practically unlimited variation without regard to valve areas and clearances. In this manner, since there are no poppet valves, an ideal shape of combustion chamber, such as spherical or near spherical, may be achieved, and the clearance volume may be made as small as desired for high compression ratios. With spark ignition the spark gap may be positioned at the center of such a combustion chamber, which is highly desirable, and with fuel injection and compression ignition the injector nozzle may be so positioned. With fuel injection and spark ignition the injector nozzle and spark plug may be positioned as desired without conflicting with valve requirements. An important advantage of the present construction is its inherent adaptability to both types of fuel injection engines.

Adjacent each cylinder head is an annular ex-

haust passage 147 communicating with exhaust ports 105. At the lower end of each cylinder is a thrust bearing ring 148 providing end bearing support for the sleeve 104. It is noted that each cylinder body proper is provided with an insert or liner, identified by the reference characters 101 and 102 which are herein referred to as the cylinders.

Figure 4 shows piston 125 at the top of its exhaust stroke, the exhaust ports 105 being practically closed and intake ports 106 and 107 being about to open for the cylinder suction stroke. Piston 126 is at the top of its cylinder compression stroke with inlet ports 110 and 111 just closed. The crankcase inlet port 130 has been open during the upward, or outward, movement of the pistons and is about to be closed by the disc 133.

Figure 7 shows piston 125 at the bottom of its said suction stroke, the exhaust ports being closed and the inlet ports being wide open and uncovered by the piston. The inward movement of both pistons has compressed the charge in the crankcase which is now admitted to the cylinder 101, the inlet ports in the other cylinder being closed on the power stroke and the crankcase inlet port 130 being covered by the disc 133.

In Figure 8 the outward movement of the two pistons has just drawn a fresh charge into the crankcase through the uncovered port 130 which is about to be closed. The directions of the rotations of the various parts are indicated by arrows in the several views.

While the cylinders are shown in opposed relation in the two embodiments illustrated, it is of course appreciated that they may be disposed at various relative angles and may be in side-by-side parallel relation. In any case, the relative crank angle for the two pistons is made such that they move outwardly and inwardly in unison so as to draw a double piston displacement volume of charge into the crankcase at each outward stroke to be compressed in the crankcase by the simultaneous inward movement of both pistons on the return stroke, admission occurring in only one cylinder at a time for alternate firing.

The principles of the invention may also be embodied in an engine of more than two cylinders. In such an engine, pairs of cylinders have pistons moving in unison in communication with a crankcase space which is common to the two cylinders, but isolated from the rest of the crankcase, each such pair of cylinders then functioning in a cycle as previously described and each crankcase space having an individual intake passage. The two cylinders comprising each pair may be adjacent cylinders, or in the case of a V or pancake engine they may lie opposite each other, one in each bank.

If desired, the herein described engine cycle may be carried out with more than two cylinders in each group provided that the pistons in such group all move outwardly and inwardly in unison to alternately charge a common crankcase space and compress the charge therein. Such an engine may be of various types such as in-line, V, pancake or radial.

Various other changes in the construction and arrangement may be made, and certain features may be used without others, it being understood that all such modifications are included within the scope of the invention, the same being limited only by the appended claims.

I claim:

1. In a four cycle crankcase compression in-

ternal combustion engine cylinder, a plurality of exhaust ports in the head end of said cylinder, a plurality of intake ports in the crankcase end of said cylinder communicating with the crankcase space, a rotary sleeve valve in said cylinder, a plurality of exhaust ports in said sleeve arranged to simultaneously open and close said cylinder exhaust ports to establish an exhaust phase of operation, a plurality of intake ports in said sleeve arranged to simultaneously open and close said cylinder intake ports to establish an intake phase of operation, and a ring gear on said sleeve to rotate same crank discs carrying said crank throws, the walls of said crankcase closely surrounding said crank discs to limit the crankcase compression space substantially to the space required between said discs for connecting rod travel, and driving means for said ring gears outside of said crankcase compression space.

2. In a pancake type opposed cylinder four cycle crankcase compression internal combustion engine, a crankcase carrying a two throw crank-shaft and a pair of cylinders having a plurality of exhaust ports in the head end and a plurality of pairs of interconnected intake ports in the crankcase end of each cylinder, a rotary sleeve valve in each cylinder, a plurality of exhaust ports in each sleeve arranged to simultaneously open and close said cylinder exhaust ports to establish an exhaust phase of operation, a plurality of pairs of intake ports in each sleeve arranged to simultaneously open and close said cylinder intake ports to establish an intake phase of operation, a ring gear on each sleeve to rotate same to produce the successive phases of four cycle engine operation crank discs carrying said crank throws, the walls of said crankcase closely surrounding said crank discs to limit the crankcase compression space substantially to the space required between said discs for connecting rod travel, and driving means for said ring gears outside of said crankcase compression space.

3. In a pancake type opposed cylinder four cycle crankcase compression internal combustion engine, a crankcase carrying a two throw crank-shaft and a pair of cylinders a plurality of exhaust ports in the head ends of said cylinders, a plurality of pairs of intake ports in the crankcase ends of said cylinders communicating with the crankcase space, pistons in said cylinders arranged to uncover all of said intake ports at the crankcase ends of their strokes, rotary sleeve valves in said cylinders, a plurality of exhaust ports in said sleeves arranged to simultaneously open and close said cylinder exhaust ports, a plurality of pairs of intake ports in said sleeves arranged to simultaneously open and close said cylinder intake ports, ring gears on said sleeves to rotate same to time the exhaust and intake phases of operation of said cylinders for alternate firing in four cycle operation crank discs carrying said crank throws, the walls of said crankcase closely surrounding said crank discs to limit the crankcase compression space substantially to the space required between said discs for connecting rod travel, and driving means for said ring gears outside of said crankcase compression space.

4. In a pancake type opposed cylinder four cycle crankcase compression internal combustion engine, a two-throw crankshaft supported in a pair of end bearings, a pair of crank throws on said crankshaft between said bearings carrying a pair of connecting rods in 180 degree relationship, crank discs on said crankshaft carrying said crank throws and lying closely adjacent opposite

sides of said connecting rods, a pair of oppositely disposed cylinders aligned with said crank throws and having their inner ends closely adjacent said crank disks, rotary sleeve valves in said cylinders, a crankcase carrying said bearings and said cylinders and having end and side walls lying closely adjacent said disks whereby said crankcase volume is substantially limited to the combined swept volume of said two connecting rods for maximum crankcase compression and driving means outside of said crankcase compression space for rotating said sleeve valves in timed relation for alternate firing of said cylinders.

5. In a pancake type opposed cylinder four

cycle crankcase compression internal combustion engine, a crankcase carrying a two throw crank-shaft and a pair of cylinders, crank disks carrying said crank throws, the walls of said crankcase closely surrounding said crank disks to limit the crankcase compression space substantially to the space required between said disks for connecting rod travel, rotary sleeve valves in said cylinders, and driving means outside of said crankcase compression space for rotating said sleeve valves in timed relation for alternate firing of said cylinders.

RALPH M. HEINTZ.
